UNITED STATES PATENT OFFICE

VERGIL MULHOLLAND, OF WEST HARTFORD, CONNECTICUT, ASSIGNOR TO HARTFORD-
EMPIRE COMPANY, OF HARTFORD, CONNECTICUT, A CORPORATION OF DELAWARE

ANNEALING GLASSWARE

Original application filed October 13, 1925, Serial No. 62,237, which is a division of Serial No. 33,977, filed June 1, 1925. Patent No. 1,560,481. Divided and this application filed May 3, 1929. Serial No. 360,113.

This invention relates to lehrs for annealing glassware, and it has particular relation to lehrs of the type embodying a tunnel which has heating and cooling flues associated therewith and through which the ware is transported, the ware being subjected therein to varying temperature environments. The inventions set forth herein also are set forth in my copending application, Serial No. 62,237, filed October 13, 1925 of which this case is a division. They likewise are set forth but not claimed in my prior Patent No. 1,560,481, granted November 3, 1925 of which the aforesaid copending application is a division, and in my prior Patent No. 1,571,137, granted January 26, 1926, reissued as Patent No. 17,263, granted April 9, 1929, of which this application is a continuation in part.

As is the case in my aforesaid Patent No. 1,571,137 and the reissue thereof, a general object of the present invention is to provide a lehr and a method of annealing glassware by the employment of which ideal temperature conditions for the annealing of the glassware are obtained. Such conditions are set out in detail in my prior patent as follows:

"If all portions of a glass article, which are being annealed, are brought to a uniform annealing temperature, and are held at this temperature a sufficient time to permit the release of strains, and if the subsequent cooling be kept uniform as to all portions of the article, it can be cooled and annealed perfectly, which result is not possible in the usual commercial lehr. This is an ideal condition for annealing and permits the article to be annealed and cooled in a minimum time, as for instance, with certain kinds of ware, in less than one hour as compared with two and one-half to five hours in the old style lehr. The nearer such ideal conditions can be approached in a tunnel lehr, the more efficient and better will be its annealing."

The matter claimed in this application, which as already stated is disclosed but not claimed in my several prior patents and in my copending application, is a novel method of annealing. The object of this method is to insure that the aforesaid ideal temperature conditions will be obtained by causing the

temperature of the gases of combustion employed in heating the lehr to be lowered to approximately the temperature at which it is desired to hold the ware, prior to bringing them into heat transferring relation with the ware.

More specifically, it is an object of the present invention to provide a novel method of annealing glassware in a tunnel lehr, wherein in the hot gases of combustion to be employed for heating the latter are cooled to a predetermined temperature prior to bringing them into heat transferring relation with the ware, and thereafter a temperature gradient is maintained in the gases throughout the annealing range, corresponding to that gradient desired in the ware. By the accomplishment of this object, the release of strains from the ware is insured and the annealing thereof may be accomplished most efficiently in the minimum of time.

Another object of the present invention is to provide a lehr of the character described, which shall be of relatively light and inexpensive structure, which may be quickly and easily assembled from a plurality of similar metallic sections, and in which the temperature in the tunnel may be easily and accurately controlled and maintained substantially uniform, so far as the environment of the ware is concerned, throughout any transverse section or zone of the tunnel.

Another object of the invention is to provide a lehr in which the heating and cooling media, flowing in their respective flues, shall be drawn through the flues by suction and shall thus be prevented from obtaining access to the tunnel through leaks or crevices that may exist or develop between the flues and the tunnel, which leakage may not only disturb the temperature therein by establishing hot or cold spots or zones, the location of which is difficult to determine and which interferes materially with the proper annealing of the ware, but would have a tendency to cause a combustion deposit on the ware. A construction characterized by the foregoing features is especially well adapted for the practice of the novel method claimed herein.

In the accompanying drawings,

Figure 1 is a diagrammatic vertical longitudinal sectional view of a lehr constructed according to the invention;

Fig. 2 is an enlarged view of the forward or receiving end of the lehr, partly in vertical longitudinal section and partly in side elevation;

Fig. 3 is a similar view of an intermediate portion of the lehr, illustrating the damper-controlled openings that regulate the temperature in the heating and cooling flues, and also the anti-friction support for the tunnel;

Fig. 4 is a vertical longitudinal sectional view of another intermediate portion of the lehr, illustrating more in detail the sectional construction of the tunnel;

Fig. 5 is a vertical longitudinal sectional view through the rear or exit end of the tunnel, illustrating the draft-producing device and the damper mechanism for controlling the drafts produced thereby;

Fig. 6 is a side elevational view, with parts broken away, of the ware-sorting table and the conveyor-driving mechanism;

Fig. 7 is a horizontal sectional view taken on line 7—7 of Fig. 2, and illustrating the internal construction of the fire box;

Fig. 8 is a vertical transverse sectional view taken on line 8—8 of Fig. 2, and illustrating the cross-sectional arrangement of the tunnel and fire box;

Fig. 9 is a vertical transverse sectional view taken on line 9—9 of Fig. 4, and illustrating the cross-sectional construction of the damper-controlled openings in the heating and cooling flues;

Fig. 10 is a view similar to Fig. 9 taken on the line 10—10 of Fig. 5, and illustrating the flues which establish communication between the heating flues and the draft-producing device;

Fig. 11 is a vertical transverse sectional view taken on line 11—11 of Fig. 6, and illustrating the construction of the mechanism for taking up slack in the endless conveyor belt;

Fig. 12 is a fragmentary horizontal sectional view through one of the expansion joints in the outer casing of the tunnel, and

Fig. 13 is a fragmentary horizontal sectional view through one of the joints between the side walls of the tunnel.

The present invention is an improvement upon the lehr disclosed in my above-mentioned prior Patents 1,571,137 and reissue No. 17,263 and, as diagrammatically illustrated in Fig. 1, briefly comprises a sectional tunnel A; a fire box B located beneath the forward or ware-receiving end of the tunnel; a plurality of heating flues C, communicating with the fire box and extending longitudinally beneath the tunnel; a plurality of cooling flues D, extending longitudinally above the tunnel; a draft-producing device E, specifically a suction fan, communicating with both the heating flues and the cooling flues;

a ware-sorting table F, located at the exit end of the tunnel; an endless conveyor G, the ware-bearing strand of which traverses the tunnel and the sorting table F, and the idle strand of which returns to the entrance end of the tunnel beneath the lehr; and a conveyor-driving mechanism H.

The several sections of the tunnel are rigidly secured together in end-to-end relation and are supported by suitable framework which includes a pair of longitudinally extending channel members 1 and transversely extending channel members 2 which are, in turn, supported by vertically adjustable pedestals 3. The tunnel is slightly inclined downward from the hot or receiving end to the cool or delivery end to cause a tendency for air to flow through the tunnel, in a direction opposite to that of the movement of the ware. This flow of air through the tunnel is preferably barely sufficient to prevent an inflow of cold air at the hot end of the tunnel without necessarily exerting a material cooling influence upon the ware.

Each of the sections of the tunnel is preferably constructed of cast iron and comprises a bottom 4, side walls 5, and a top 6. The bottoms 4 of these sections are of shell-like structure, being formed with a plurality of parallel longitudinally extending ports 7 which, when the sections are arranged in end-to-end relation, constitute the heating flues C. The forward edges of the partitions between the ducts 7 are cut away, as indicated at 7a, to insure an equal draft in all of the flues C.

The forward or entrance end of the bottom 4 of the first section of the tunnel is rigidly bolted, as indicated at 8, Fig. 2, to the rear end of a box 9 which, in turn, is rigidly bolted, as indicated at 10, to the channels 1 of the supporting frame of the lehr and which constitutes the forward end of the heating flues. The forward end of the bottom 4 of each of the succeeding sections of the tunnel is bolted to the rear end of the bottom of the preceding section, as indicated at 11, Fig. 2. The rear end of each of the bottoms 4 is supported by rollers 12 which ride on rails 13 carried by the channels 1.

The rear end of the box 9 and the rear ends of each of the bottoms 4 are provided with seats 14 for telescopic engagement with reduced flanges 15 provided on the forward ends of each of the bottom members 4. The joints thus formed between the several bottom members are sealed with a suitable refractory cement so as to not only prevent the gases traversing the heating flues C from leaking into the tunnel, and causing the hot spots and carbon deposits above referred to, but to also prevent air from the outer atmosphere from leaking into the heating flues and interfering with the control of the temperatures therein.

The side walls 5 of the tunnel sections are bolted to their respective bottom members 4, as indicated at 16, and their forward edges are formed with offset flanges 17 (Fig. 13) for overlapping engagement with the rear edges of the corresponding walls of the preceding section.

The top members 6 of all of the sections of the tunnel are supported by the side walls 5 and are provided with a plurality of longitudinally extending corrugations 18 which provide a roof for the tunnel having a relatively large heat radiating surface in comparison with the width of the tunnel. It will be noted, from an inspection of the drawings, that these tops are of two types. For approximately one-third of the length of the tunnel, commencing at its entrance end, the tops 6 are of open construction as illustrated in Fig. 8, but for the remainder of the distance along the tunnel, the tops 6 are also of the shell-like structure best shown in Fig. 9, being formed with a plurality of parallel longitudinally extending ports 19, which, when the tops are arranged in end-to-end relation, constitute the cooling flues D.

The lehr is heated by a burner 20 which projects a flame through an opening 21 into a combustion chamber 22 provided in the fire box B (Fig. 7). The flame from the burner, upon entering the chamber 22, first impinges upon an angularly disposed baffle 23 which deflects it in the directions indicated by the arrows in Fig. 7. From the chamber 22, the products of combustion pass forwardly through an opening 24, provided in a wall 25 and into a mixing chamber 26, where they first encounter a baffle 27 which deflects them rearwardly and distributes them in a lateral direction throughout the chamber. A port 28 (Figs. 7 and 8) establishes communication between the outer atmosphere and the chamber 26 directly to the rear of the baffle 27, and supplies diluting air to the products of combustion as they enter the chamber 26. The amount of air passing through the port 28 may be controlled by a damper 29 provided on the side of the fire box.

The combustion chamber 22 and the mixing chamber 26 are both provided with inner linings 30 of refractory material and with outer linings 31 of heat-insulating brick, which is surrounded by a powdered-insulating material 32, such as kieselguhr, or the like. This structure is contained within a metallic casing 33, which is mounted upon adjustable legs or pedestals 34 and which constitutes the forward support for the channel members 1.

From the chamber 26 the products of combustion pass through spaced openings 35, provided in the front wall thereof, and into a draft-equalizing box 36, thence upwardly into a draft-regulating box 37, and thence

into the box 9 which forms the forward end of the heating flues C. Pipes 38 are provided for admitting air from the outer atmosphere into the box 36. These pipes are provided with caps 39, having air-inlet openings formed therein, and may be individually exchanged for caps having larger or smaller openings to admit varying quantities of air into the box 36 in order to distribute the draft equally transversely of the tunnel. The openings in these caps may also be employed to observe the character of the combustion in the fire box. A damper 40 is provided in the box 37 in order to regulate the amount of the draft in the fire box B and in the heating flues C.

Both the heated gases and the cooling air are drawn through their respective flues C and D at sub-atmospheric pressure by a common draft-producing device E comprising a motor driven suction fan 41 which is mounted on the top of the tunnel adjacent to the exit end thereof. This fan communicates with a drum 42 which in turn communicates with a pair of vertical flues 43 disposed one on each side of the lehr. These flues communicate at their lower ends with a transverse flue 44 located beneath the lehr and which in turn communicates with all of the heating flues C through a longitudinally extending upwardly inclined flue 45 (Fig. 5). The flue 45 is provided with a damper 46 which may be operated to control the draft in the heating flues by means of a rod 47 which is threaded into the hand wheel 48.

The drum 42 of the draft-producing device also communicates with the cooling flues D in the top of the tunnel through the medium of a longitudinally extending conduit 49 disposed above the lehr, and which communicates at intervals with all of the cooling flues D through stacks 50 (Figs. 3 and 4). These stacks are provided with dampers 51 which may be selectively operated to regulate the amount and location that the cooling air is drawn out of the cooling flues. It will be noticed from an inspection of Fig. 1 that the cooling air is drawn through the flues D in a direction opposite to that of the flow of the heating gases in the flues C.

A damper 52 is also provided in the conduit 49, as shown in Fig. 5, and may be operated to control the draft in all of the cooling flues by means of a rod 53 which is threaded into a hand wheel 54.

The temperature in the flues C may be regulated by admitting diluting air from the outer atmosphere into these flues through a plurality of stacks 55 which are arranged at intervals lengthwise of these flues. Dampers 56 are provided in the stacks 55 to enable the operator to regulate the amount and the location where such diluting air is admitted into the heating flues, whereby the desired temperature drop or curve in these

flues and in the tunnel may be obtained. The dampers 51 and 56 are provided with operating handles 57 and 58 respectively, having calibrated segments 59 and 60 formed integrally therewith by means of which the distances that these dampers are opened may be accurately determined.

The rear ends of the heating flues C are closed to the outer atmosphere, as indicated 10 at 60a in Fig. 5, and inasmuch as the flues 43 communicate with the flues C forward of the last stack 55 in these flues, cooling air will flow in the flues C in a forward direction for a short distance adjacent to the exit end of 15 the tunnel where it is desired to hasten the cooling of the ware.

By properly adjusting both the dampers 51 and 56 in the stacks 50 and 55 respectively, the desired temperature gradients may be obtained 20 in the flues C and D, and in the portions of the tunnel adjacent thereto. That is to say, the character of the temperature curves obtained by plotting temperatures as ordinates against distances along the lehr as 25 abscissæ, in both the heating flues and in the cooling flues is determined by the number and location of the dampers that are opened to the outside atmosphere, and the degree to which such dampers are opened. For example, the 30 less the amount of cooling air from the outer atmosphere that is permitted to enter the forward or hotter portions of the heating flues C, the greater distance will the heat in these flues influence the temperatures there- 35 in; and the less the amount of cooling air that is allowed to escape from the rear or cooler ends of the cooling flues D, the greater distance will the cooling air traverse these flues. It, therefore, follows that by regulat- 40 ing the amount that the gases in the heating flues are diluted and cooled by outside air, and by regulating the amount of cooling air escaping through the stacks 50 from the cooling flues D and by also determining the lo- 45 cation of the dampers that are adjusted, the resultant temperature gradients of the top and bottom portions of the tunnel may not only be controlled at will, but the point or zone of maximum drop in the temperature 50 curves may be shifted longitudinally of the tunnel.

By thus heating the floor of the tunnel to cause upwardly moving convection currents and by cooling the top of the tunnel to cause 55 downwardly moving convection currents and by independently regulating the degree of heating and cooling, the rate of movement of the convection currents in the tunnel may be controlled at will, thereby rendering it 60 possible to obtain a substantially uniform temperature, so far as its effect upon the ware is concerned, in a vertical direction in any transverse section or zone in the tunnel.

Dissipation of heat from the tunnel and 65 the heating flues is minimized by surround-

ing the tunnel with heat-insulating material 61 in the form of powdered kieselguhr or the like. This material is contained within an outer casing comprising the following parts: 70 horizontally extending plates 62, which are supported beneath the tunnel by the channels 1 and 2; angle plates 63, which are secured to the sides of the bottoms 4 and which overhang the rollers 12 (Fig. 9); side plates 75 64 which are secured at their lower edges to the angle plates 63 and which are maintained in spaced relation with the sides of the tunnel by spacer bolts 65; and top plates 66, which extend horizontally above the tunnel 80 in spaced relation thereto and which are secured at their outer edges to the side plates 64. Expansion joints are provided between the vertical edges of the side plates 64 and each comprises a channel 67 and a spacer 68 85 which are secured to one of the plates 64 and which slidably retain the overlapping edge of the adjacent side plate (Fig. 12).

The thickness of the insulation 61 may be reduced toward the rear end of the lehr, as 90 shown in Fig. 4, and may be entirely dispensed with adjacent to the exit end of the tunnel, as shown in Fig. 5.

The sorting table F consists of a plurality of spaced parallel longitudinal bars 69 (Figs. 6 and 11) which are supported at their forward ends by the frame of the lehr, and at their rear ends by a frame 70 of the belt driving mechanism H. Rollers 71 are carried at spaced intervals by the bars 69, and provide a support for the conveyor as it emerges from the tunnel bearing the annealed ware. The table F is of sufficient length to permit several persons to stand side by side on each side of the table to inspect and remove the ware from the conveyor G for packing. The conveyor G and the table F are sufficiently narrow to permit easy access, from either side of the table, to ware located in the central portion of the conveyor.

The conveyor G comprises an endless belt of flexible open structure, the ware-bearing strand of which lies flat upon the cast iron bottom members 4, which constitute the bottom of the lehr tunnel, and upon the rollers 71 of the receiving table F.

As best shown in Fig. 6, the conveyor, as it advances over the end of the receiving table F, passes over a roller 72 journaled in the frame 70 and thence forwardly and around a driving drum 73 which is mounted on a shaft 74 journaled in the frame 70. At the point where the belt leaves the drum 73, it passes over and rearwardly around a roller 75 which is journaled at its ends in side blocks 76, mounted in ways 77. The drum 73 and the roller 75 are provided with resilient anti-slipping coverings 78 and 79 respectively, composed of rubber or the like, so as to present a tractive surface to the belt and insure a positive driving contact there- 110 115 120 125 130

with. The roller 75 is maintained in gripping contact with the belt G by jack screws 80 which are threaded in the ways 77 and which bear against the side blocks 76.

5 The drum 73 and the roller 75 are rotated by a sprocket wheel 81 which is driven in any preferred manner. The sprocket wheel 81 is mounted on a shaft 82 which carries a worm 83 meshing with a worm wheel 83a carried 10 by a shaft 84. A pinion 85 is also keyed to the shaft 84, and meshes with a gear wheel 86 mounted on a shaft 87. A pinion 88 is also keyed to the shaft 87 and meshes with a gear wheel 89 carried by the drum 73. The gear wheel 89 meshes with a gear wheel 90 on the roller 75, whereby both the drum and the roller are driven at the same peripheral speed.

15 The conveyor belt G, after passing around the roller 75, passes forwardly and beneath a roller 91 and thence upwardly and rearwardly over an idler roller 92. The idler roller 92 is mounted on a shaft 93, provided with gear wheels 94 at each end which are mounted on 20 rack bars 94a carried by the bars 69. By rotating the shaft 93 by means of a handle 95, the roller 92 may be shifted longitudinally of the table F to take up any slack in the conveyor. After leaving the roller 92, the belt 25 G passes upwardly and forwardly over a roller 96 carried by the bars 69, and thence forwardly beneath the lehr where it is supported at intervals by rollers 97 which are mounted on the pedestal 3. At the forward 30 or receiving end of the lehr, the lower strand of the conveyor G is supported between rollers 98 mounted beneath the fire box B (Fig. 2). As the belt leaves these rollers, it passes upwardly and parallel to the front 35 end of the fire box and thence over a roller 99 disposed adjacent to the entrance of the tunnel. From the roller 99 the belt passes over the box 9 and beneath a guard plate 100 and into the front end of the lehr tunnel.

40 The entrance end of the tunnel is provided with a door 101 which is mounted in ways 102 for vertical sliding movement. This door may be raised or lowered, to close the upper portion of the tunnel but permitting 45 sufficient clearance for ware to pass therebeneath by means of rods 103 which are threaded into hand wheels 104 mounted on a frame 105. When the door has been adjusted to the desired height, it may be clamped in 50 position by screws 106 provided in the ways 102.

55 The exit end of the tunnel is provided with a door 107 which is hinged at its upper edge to the top 6 of the last section of the tunnel 60 and which is provided with arcuate side flanges 108 to prevent an influx of excess air from the outer atmosphere into the tunnel. The door may be opened sufficiently to permit ware to pass therebeneath and main- 65 tained at such height by a bar 109 which is

adapted to be adjustably secured to a bracket 110 carried by the base of the draft-producing device E.

70 From the foregoing it will be apparent that I have provided a lehr of very rugged and durable structure and one that may be assembled very quickly and easily from a plurality of similar and interchangeable sections. Also, it will be apparent that by my construction and method of drawing the heating gases 75 and the cooling air through the several flues at subatmospheric pressure, the injurious effects of leakage of these media into the tunnel is reduced to a minimum. Furthermore, supporting the tunnel throughout its entire 80 length by anti-friction devices renders it possible to eliminate expansion joints or other joints between the sections of the tunnel through which leaks may exist or may develop, and permits the tunnel to expand 85 lengthwise as a unit on its support.

90 Certain structural features herein shown and described are not claimed herein, but are specifically claimed in certain of my copending applications. For example, no claim is made herein to the feature of drawing heated gases through a portion of the flues beneath the tunnel to heat a portion of the tunnel and causing cold air to flow in the opposite direction through another portion of the same flues 95 to cool the exit end of the tunnel, inasmuch as this matter is claimed in my co-pending application filed August 27, 1925, Serial No. 52,751, now Patent No. 1,588,603, dated June 15, 1926.

100 It is obvious that the lehr herein disclosed provides flues for the heated gases which are separated from the tunnel by relatively thin cast iron walls which make for rapid heat exchange between the gases and the glassware 105 in the tunnel, and provides a fire box specifically provided with means to regulate the admission of air to dilute the products of combustion passing therefrom into the flues. 110 As the glassware is to be passed through the tunnel, preferably in close proximity to the walls of the flue and separated therefrom by a conveyor of flexible open-work structure, which does not hinder materially the rapid transference of heat from the ware to and through the flue wall, it is obvious that this lehr should be operated and the controls so used that the products of combustion from the fire box be sufficiently diluted with air prior to their admission into the flues that 120 their temperature closely approximates that of the glassware at the "soaking" period, that is, during the time that permanent strains are being released therefrom. When extremely light weight ware is being annealed, the gases 125 are usually supplied to the flue at a temperature slightly higher than this desired "soaking" temperature to compensate for the greater cooling during the shaping and transferring operations, while with very heavy

130

ware, the flue gases may be at a slightly lower temperature than the aforesaid "soaking" temperature. Such a control of the condition of the gas at or near the beginning of the flue permits the relatively high temperature of the gases to be continued a material distance down the lehr, without the introduction of additional heat and without the use of too high temperatures adjacent to the entrance end of the lehr and during the "soaking" period, such as would be required were it not for the greatly increased total volume of gases per unit of time due to the initial dilution of those gases to bring them down to the annealing temperature, as above described.

The provision of the above-recited elements in my lehr, in lieu of the relatively poor heat conducting flues and conveyors of high heat mass of the prior art, permits the use of larger volumes of gases at lower temperatures to obtain the same temperature in the tunnel; and the provisions made by me for the rapid transference of heat from the tunnel to the flue and vice versa permit accurate and flexible control of the temperature gradients in the flue and hence in the ware in the tunnel. The use of relatively large volumes of gas at low temperatures is also a material factor in the economical use of the lehr, inasmuch as it permits of the use of a relatively small amount of fuel to produce an initially small amount of hot gases which are later diluted.

The various features of the invention herein described as incorporated in a single organized apparatus may be used separately or in other combinations, and various modifications may be made in the arrangement and construction of the parts, and in the method of cooling the article to be annealed. For some uses, as for example, for the handling of only one kind of ware, some of the adjustments and other provisions for handling varied kinds of ware may be dispensed with. Again, by mounting the tunnel on anti-friction devices, the tunnel may be made integral throughout its length. In this and in other ways, the method and apparatus herein described and shown may be modified within the scope of the appended claims.

I claim as my invention:

1. The method of annealing glassware that comprises continuously passing the ware through an elongate tunnel, generating hot gases by combustion, passing said gases adjacent to the ware in the tunnel and in good heat transferring relation therewith, and reducing the temperature of said gases between the point of generation thereof and the point at which they first come into good heat transferring relation to the ware to first present the gases into such relation at approximately the temperature at which it is desired to hold the ware for the release of permanent strains therefrom.

2. A lehr for annealing glassware, comprising an elongate tunnel, a conveyor of flexible openwork material for moving articles of glassware therethrough, a flue having a common metallic wall with said tunnel, means for supplying heated gases to said flue at a point adjacent to the ware-receiving end of said tunnel, and means adjacent to the inlet end of said flue to dilute said gases with air to bring them to a temperature approximating that at which it is desired to hold the ware for permitting the release of permanent strains.

3. A lehr for annealing glassware comprising a tunnel, a flue extending longitudinally beneath said tunnel, a fire box disposed beneath the receiving end of said tunnel and communicating with said flue, a port for admitting air from the outer atmosphere into said fire box to dilute the gases therein, and a plurality of adjustable openings located between said fire box and said flue for admitting regulable quantities of atmospheric air into the passage therebetween to distribute the draft uniformly transversely of said flue.

4. A lehr for annealing glassware comprising a tunnel, a plurality of flues extending longitudinally beneath said tunnel, a fire box disposed beneath the receiving end of said tunnel and communicating with said flues and including a combustion chamber, a mixing chamber and a draft equalizing chamber, means for admitting diluting air into said mixing chamber, and a plurality of openings arranged at intervals transversely of said equalizing chamber and communicating with the outer atmosphere for admitting regulable quantities of air into said chamber to distribute the draft uniformly transversely of said flues.

5. A lehr for annealing glassware comprising a tunnel, a temperature controlling flue associated therewith, a fire box for supplying hot gases to said flue disposed adjacent to the entrance end of said tunnel, means associated with said fire box for admitting atmospheric air to dilute the gases in said fire box to reduce their temperature substantially to that desired at the entrance end of said flue, and a plurality of laterally spaced inlet passages for admitting additional atmospheric air to said gases to distribute the draft in said flue laterally thereof.

6. A lehr for annealing glassware comprising a tunnel, a temperature controlling flue associated therewith, a fire box for supplying hot gases to said flue disposed adjacent to the entrance end of said tunnel, a burner for projecting a flame into said fire box, means adjacent to said burner for admitting combustion supporting air to said fire box, means for admitting additional air to said fire box to dilute the products of combustion and reduce their temperature to substantially that desired at the entrance end of said flue, and a

plurality of laterally spaced controllable air inlet ports communicating with the passage of the diluted products of combustion at a point between said fire box and said flue for admitting additional air to control the draft distribution laterally of said flue.

5. The method of annealing glassware which comprises continuously passing the ware through an elongate tunnel, generating hot gases by combustion, passing said gases adjacent to the ware in the tunnel and in good heat transferring relation therewith, reducing the temperature of said gases adjacent the point at which they first come into good heat transferring relation to the ware to first 10 present the gases into such relation at approximately the temperature at which it is desired to hold the ware for the release of permanent strain therefrom, and maintaining 15 a temperature gradient in the gases substantially the same as that desired in the ware throughout the annealing range.
